LIGHTWELL

Elliott P. Ross, Forest Hills, and James V. Lawrence, Astoria, N. Y., assignors to Ford Instrument Company, Inc., Long Island City, N. Y., a corporation of New York

Application November 28, 1933, Serial No. 700,068

18 Claims. (Cl. 240—2)

This invention relates to lightwells adapted to be combined with a wall of a chamber that has a relatively dark interior whereby objects within the chamber may be clearly observed from the exterior thereof. More particularly, the invention concerns lightwells for illuminating devices, such as dials and other indicators, operable mechanism and gyroscopes that may wander, all or any of which are inside the casings of fire control instruments. The manner of illuminating is such that the danger of an enemy detecting the presence of the instruments through observance of their illumination is reduced to a minimum.

It is an object of the invention to provide a device of this character which shall be of simple, compact, reliable and inexpensive construction, and which gives ready access to lamps and other internal parts of the device from the exterior of the casing or other object to which the lightwell is attached, such access being had without the removal of the lightwell as a whole from the object with which it is combined.

Other features appearing hereinafter are, of course, to be understood as forming part of the present invention.

Referring to the drawings, which illustrate a preferred embodiment of the invention,

Fig. 1 is an elevational view showing the exterior of the lightwell;

Fig. 2 is a vertical central section of the lightwell taken on the line 2—2 of Fig. 3;

Fig. 3 is a view of the end of the lightwell that is provided with a removable cover, parts being broken away to disclose portions of the disk end 35 of the lamp holder and the end of the lightwell which it closes;

Fig. 4 is a transverse section of the lightwell taken substantially on the line 4—4 of Fig. 2, and illustrating certain electrical connections, as 40 well as the slideable mounting for the lamp holder;

Fig. 5 is a view of the light-emitting end of the lightwell, part of the gasket thereat being broken away;

Fig. 6 is a horizontal transverse section of the lightwell taken on the line 6—6 of Fig. 3, some of the parts being shown in plan; and

Fig. 7 is a perspective view of the lightwell with the cap and lamp holder moved into position to give access to the lamps and the interior 50 of the well, parts being shown in section.

In the drawings, 1 represents the major cylindrical part of the main body portion of the casing of the lightwell which has an end portion 2 of slightly reduced diameter. At the junction 55 of the cylindrical portions 1 and 2 of the main body

portion of the lightwell, is an exterior rectangular attachment flange 3, lying against one side of which is a gasket 4 of cork or other suitable material. As shown in Figs. 1 and 2, the opposite side of the gasket 4 lies against the flat surface of a boss 5 of a casing 6 of an instrument the interior of which requires illumination for dials and the like. The shape of the gasket 4 as shown in Fig. 5 corresponds to the contour of the flat surface of the boss 5 the gasket sealing the opening in the casing 6 through which the end portion 2 of the lightwell extends. Screws 7, shown in Fig. 1, pass through holes in the attachment flange 3 and gasket 4 and are threaded into the boss 5, thereby holding the cylindrical body portion of the lightwell casing securely to the instrument casing 6. The gasket 4 is thus compressed and seals the opening in the instrument casing 6 through which the lightwell passes, so that water or moisture cannot enter the instrument casing, which it will be understood is also sealed at all other necessary places for this purpose.

Applied to the end 2 of slightly reduced diameter of the cylindrical body portion of the lightwell casing is a transparent or translucent disk 8, which forms a window for the emission of light from the lightwell. This disk is preferably of unshatterable material, such as translucent bakelite, and is provided with annularly arranged holes therethrough in proximity to its circumference, screws 9 passing through these holes and being screwed into the wall of the end 2 of the lightwell casing, as shown in Figs. 1, 2 and 5. As it is desired to exclude dampness from the interior of the instrument, a self-hardening substance, such as a weather-proof varnish, is interposed between the edge of the end 2 of the lightwell casing and the circular marginal portion of the disk 8, thus effectively sealing the lightwell at this place.

At the other end of the cylindrical body portion 1 of the lightwell casing there is a circular flange 10 the periphery of which is provided with screw threads. Screwed onto the flange 10 is the internally threaded portion of a cap 11, which 45 cover is provided with external spaced apart annularly arranged bosses 12, which afford an excellent finger grip for applying or removing the cap.

The cap 11 has a central circular hole through 50 which a cylindrical stud 13 extends, the stud preferably having a slightly rounded end in the rear of which the stud is provided with a semi-cylindrical groove in which a split ring 14 is seated. Between the ring 14 and the flat cir- 55

cular surface of the cap 11 is a washer 15 which takes the wear occasioned by screwing the cap onto and off the flange 10 of the body portion of the lightwell casing. The stud 13 is integral with an enlarged circular head or disk 16 of a lamp holder, the body portion 17 of which is integrally formed with the disk 16. Such body portion 17 of the lamp holder is, in one direction, of much less dimension than the internal diameter of the main portion 1 of the cylindrical lightwell casing, and in a direction perpendicular to the first mentioned direction approaches the lightwell casing much more closely, but leaves room for electrical conductors that are referred to more fully hereinafter. The cross sectional contour of the body portion 17 of the lamp holder is seen in Fig. 4 to have parallel sides connected at opposite ends by semi-circular sides. Ribs 18 and 19 are integral with and strengthen the connection between the body portion 17 of the lamp holder and disk portion 16 thereof.

On its outer side the disk 16 is provided with a central boss 20 between which and the flat circular interior surface of the cap 11 a wear washer 21 is interposed, the washer 21 being slipped over the stud 13. In extending from its central boss 20 to its circumference, the disk 16 is attenuated, its inside surface being flat and overlapping the end of the slightly larger portion 1 of the lightwell casing, which contains an annular groove in which lies a circular gasket 22. The flat side of the lamp holder disk 16 is forced against the gasket 22, which is compressed when the cap 11 is screwed onto the lightwell casing. Therefore, this end of the lightwell casing is effectively sealed, as is its opposite end.

As best shown in Figs. 2 and 4, the body portion 17 of the lamp holder has a peculiar recess which comprises two parallel cylindrical spaces connected by an intermediate space. Lamp sockets 23 are permanently retained in the cylindrical spaces of the lamp holder, and lamp bulbs 24 are removably held in the sockets 23 in the usual manner. Figs. 2 and 4 show bare wires 25 which electrically connect the terminals of the lamp sockets 23 for proper inclusion in a lighting circuit. Bared ends of a pair of insulated conductors 26 are individually looped around and preferably soldered to the respective terminal-connecting wires 25. The insulated conductors 26 adjacent to their bared looped ends lie in the intermediate space between the lamp sockets 23, and extend to and through a somewhat elongated aperture 27 in one of the flat walls of the body portion 17 of the lamp holder, as shown in Figs. 2, 4 and 6.

Emerging from the lamp holder through aperture 27, the conductors 26 respectively extend in opposite directions following diagonally to some degree the cross sectional contour of the body portion 17 of the lamp holder toward its disk 16 and approximately to the side of the lamp holder that is opposite to the side from which the conductors emerge. Thereafter each conductor 26 is loosely bent to extend toward the opposite end of the lightwell, and in so extending passes under one of a pair of oppositely projecting guide pins 28 that are riveted to or otherwise carried by a U-shaped guide bracket 29, which is referred to more in detail hereinafter. Passing from under the guide pins 28, the conductors 26 further extend on opposite sides of the U-shaped bracket 29 and an attachment lug 30

therefor to a pair of terminals 31, as shown in Figs. 2 and 6.

Both of the terminals 31 are of the same construction, and one of them is shown in section in Fig. 2, where it is shown to have an inwardly extending cylindrical extension 32. This extension has a stepped cylindrical recess into the larger outer end of which a wound or bound end of the insulated conductor 26 associated therewith is entered. Beyond this insulated end of the conductor 26 a bared portion of the latter extends into the portion of the recess that is of smaller diameter and is retained in place by solder 33, which is applied through a hole 33'.

Referring to Figs. 2 and 6, it is seen that the extension 32 of each terminal 31 projects inwardly from a base plate 34 one side of which lies against the inside of the window disk 8, being held to the latter by a screw 35. Projecting from the opposite side of the base plate 34 of each terminal 31 is another extension 36, which contains a screw threaded hole, the extension extending slightly beyond the outer face of the window disk 8. A substance, as varnish, effects a seal between the disk 8 and the base plates 34, extensions 36 and screws 35. Lying directly against the end of each extension 36 is a conductor terminal clip 37, having a drifted through boss 38 against which the head of a screw 40 bears. The threaded shank of the screw 40 is screwed into the threaded hole in the extension 36 thereby clamping the conductor terminal clip 37 tightly to the extension 36, as shown in Fig. 2. A conductor 41 is attached to each terminal clip by having the ears 42 of the clip bent around a bared end of the conductor 41 and by consolidating these metallic parts with solder, if desired.

From Fig. 2 it is clear that the screws 35 prevent the lightwell terminals 31 from turning about the axes of their respective cylindrical extensions 36, which fit in holes of corresponding shape in the window disk 8, since each screw 35 fits closely in a hole in this disk and is threaded into the base plate 34 of its associated lightwell terminal 31, the axis of each screw 35 being offset from the axis of the extension 36 of the terminal 31 into which such screw 35 is entered. Similarly, the external conductor terminal clips 37 are prevented from turning, since their upper ends have semi-circular recesses forming prongs that embrace the heads of screws 35, so that the conductor terminal clips 37 cannot turn about the shanks of the screws 40. The conductors 41 lead to and from the conductors of a lighting circuit in the usual manner.

As well shown in Figs. 2, 6 and 7, the closed end of the U-shaped guide bracket 29 has a screw 43 passing therethrough, which screw is threaded into a screw hole in the lug 30 that is preferably cast on the interior of the portion 2 of the lightwell casing. The face of the lug 30 against which the adjacent side of the guide bracket 29 lies has been shown to be coincident with a shoulder formed in consequence of the difference in the internal diameters of the portions 1 and 2 of the lightwell casing. A pad 44, shown in Fig. 2, underlies the U-shaped guide bracket 29, which guide bracket bears on the pad, and, therefore, cannot be rotated to become angularly or otherwise displaced from its normal position.

The parallel arms 45 of the U-shaped guide bracket 29 are provided with guide slots 46, shown to best advantage in Figs. 2, 4 and 7. Integral with the body portion 17 of the lamp

holder and projecting from one side thereof to extend between the parallel arms 45 of the guide bracket 29 is a lug 47. A pin 48 extends through a hole near the free end of the lug 47 with such tight fit as to be rigidly combined with the lug, this pin having such length and disposition that it extends from opposite sides of the lug 47, its opposite end portions passing through the slots 46 in the parallel arms 45 of the bracket 29 and to short distances therebeyond. As the width of the lug 47 is substantially equal to the distance between the arms 45, the lug is guidedly slidably longitudinally of the bracket 29, as is the lamp holder, for a purpose presently explained.

In the normal operation of the lightwell, its parts are in the positions best appreciated from Figs. 1, 2 and 6, so that with the electric current flowing therethrough the lamp bulbs 24 glow and light passes through the disk-like window 8, illuminating the interior of the instrument or chamber with which the lightwell is associated. The gasket 4 seals the interior of the instrument or chamber at the place of application of the lightwell, and, as the lightwell is itself sealed, as previously explained, and the instrument is also otherwise sealed, no moisture-laden air can enter the instrument or chamber.

At such times as it is desired to inspect or replace the lamp bulbs 24, or other interior parts of the lightwell, the first step is to grasp and turn the cover 11, which thereupon is screwed off the threaded flange 10. Since the cover 11 is rotatively mounted on the stud 13 that is an integral part of the lamp holder, and is captive on this stud between the wear washers 15 and 21, the lamp holder is withdrawn with the cover. As this occurs, the lamp holder lug 47 slides longitudinally of and between the parallel arms 45 of the bracket 29, the opposite ends of the pin 48 sliding in the guide slots 46 of the arms 45, and at the same time preventing rotation of the lamp holder. Thus, there is no frustrative twisting of the electrical conductors 26, or other relative displacement of internal parts that might tend to retard the withdrawal of the lamp holder from the casing of the lightwell.

Upon the release of the threads of the cover 11 from those of the flange 10 of the casing, the turning of the cover is stopped, but the outward pull on it is continued. This pull, however, is terminated by the ends of the lamp holder pin 48 reaching the outer ends of the slots 46 in the parallel arms 45 of the bracket 29. The pin 48 so stopped becomes a pivot for the assembly comprising the cover and the lamp holder, and this assembly is then turned about the axis of pin 48 to a position such as is shown in Fig. 7. The lamp holder and the lamp bulbs 24 carried thereby have then been fully retracted from the casing of the lightwell and positioned so that the lamp bulbs may be examined or replaced.

During the withdrawal of the lamp holder, the flexible electrical conductors 26 bend and shift their positions to some degree, but the guide pins 28 and the adjacent portions of the interior surface of the wall of the lightwell casing adequately control the displacements of the conductors 26, as may be understood from Figs. 2, 4, 6 and 7, so that these conductors are guided to remain in positions from which they may resume their former dispositions when the lamp holder is restored to its normal position in the casing.

To make such restoration, the assembly comprising the cover 11 and the lamp holder is turned about the axis of pin 48 in the direction

reverse to that of the first mentioned turning thereabout, and is pushed toward the open mouth of the lightwell casing until the cover 11 is in position to be again screwed onto the threaded flange 10 of the casing, which is then done. As the cover 11 is screwed into place, the disk portion or head 16 of the lamp holder comes against the gasket 22 in the open end of the lightwell casing, continued turning of the cover 11 pushing the disk 16 against the gasket 22 to compress it and again seal this end of the lightwell. The parts of the lightwell will have then resumed their normal positions, the lamp holder lug 47 and pin 48 having slid reversely along the arms 45 of the bracket 29 and the electrical conductors 26 having moved back to again assume their former positions.

In the lightwell herein disclosed the casing, lamp holder and cover are permanently interconnected in such manner that all of the parts of the device are maintained constantly connected, and so as to be in definite fixed relation to each other with the interior of the lightwell sealed to protect its interior elements, or to be loosely articulated and adjustable to give ready access thereto.

While a particular embodiment of the invention has been shown and described, it will be understood that it may be embodied in other forms, and that various changes in its structural parts may be made without departing from the principle of the invention as defined in the appended claims.

We claim:

1. In a lightwell, a casing comprising a body portion having an open end and a removable cover for said open end, a lamp-carrying holder normally in said casing, and adjustable mechanical connections combining said holder and body portion for relative linear and angular movements enabling the withdrawal of said holder and a turning thereof into an accessible position while remaining connected to said body portion.

2. In a lightwell, a casing comprising a body portion having an open end, a light permeable part and a detachable cover for said open end, a lamp-carrying holder normally in said casing, and adjustable mechanical connections combining said holder, cover and body portion for relative linear and angular movements enabling the withdrawal of said cover and holder from said body portion and a turning thereof into an accessible position while remaining connected to said body portion.

3. In a lightwell, a casing comprising a body portion having an open end, a sealed light-permeable portion and a removable cover for said open end, an interruptible seal between said open end and cover, a lamp-carrying holder normally in said casing, and adjustable mechanical connections combining said holder and body portion for relative linear and angular movements enabling the withdrawal of said holder and a turning thereof into an accessible position while remaining connected to said body portion.

4. In a lightwell, a casing comprising a body portion having an open end, a removable cover attached to said open end, an interruptible seal between said open end and cover, a light-permeable closure in sealed relation to said body portion and an attachment member combined with said body portion provided with a seal and adapted to be affixed and sealed to an apertured portion of a housing to be interiorly illuminated, a lighting device normally in said casing, and ad-

justable mechanical connections combining said device and body portion for relative linear and angular movements enabling the withdrawal of said device from said casing and a turning thereof into an accessible position while remaining connected to said body portion.

5. In a lightwell, a casing comprising a main body portion having an open end, means for the egress of light, and a removable cover for 10 said open end, a fixedly positioned guide in said casing, and a displaceable lighting device normally positioned in said casing engaging said guide for sliding and pivotal movements enabling the withdrawal of said device from said casing 15 into an accessible position and its return into said casing when said cover is removed.

6. In a lightwell, a casing comprising a main body portion having an open end, a portion for the egress of light and an external cover, an interior disk member covering the open end of said main body portion, sealing means between said disk member and open end, said external cover being rotatively mounted on said disk member and attachable to the open end of said body portion, a fixed guide in said casing, and a displaceable lighting device normally in said casing extending inwardly from said disk member and engaging said guide for sliding and pivotal movements enabling the withdrawal of said device from 30 said casing into an accessible position when said cover is detached from said body portion of said casing and its return into the latter.

7. In a lightwell, a casing comprising a body portion having an open end and a window and a 35 detachable cover for said open end, a lamp-carrying holder normally in said casing, a guide fixed in the interior of said body portion and having parallel slotted arms extending from an inner part of said body portion toward its open end, 40 and an element rigid with said holder having projections entered into the slots of said arms, said holder being withdrawable when said cover is detached until said projections engage the outer ends of the slots in said arms, whereupon said 45 holder is adapted to be turned into an accessible position outside of the body portion of said casing.

8. In a lightwell, a casing comprising a body portion having an open end and a window and a 50 detachable cover for said open end, an internal guide extending longitudinally of said body portion toward its open end, a lamp-carrying holder normally in said casing engaging said guide, said cover being revolvably mounted on said holder for 55 attachment to and removal from said body portion, said cover and holder being withdrawable from their normal positions under the control of said guide and being movable into an accessible position exteriorly of said body portion while remaining connected thereto.

9. In a lightwell, a casing comprising a body portion having an open end and a window and a 60 detachable cover for said open end, an internal guide extending longitudinally of said body portion toward its open end, a lamp-carrying holder normally entered into said casing engaging said guide for sliding and pivotal movements, said cover being revolvably mounted on said holder for attachment to and removal from said body 65 portion, removable retaining means for said cover, said cover and holder being movable under the control of said guide into an accessible position exteriorly of said body portion while remaining connected thereto.

75 10. In a lightwell, a casing comprising a main

body portion having an open end, a portion for the egress of light and a cover, a displaceable lamp holder normally in said casing, a guide member and a part relatively movable to each other, one being in fixed relation to said body portion and the other being rigid with said lamp holder and co-acting to restrain said holder from rotation, said cover being attachable to and removable from the open end of said body portion by rotary movement, said lamp holder being withdrawable under the control of said guide member and part by sliding and pivotal movements into an accessible position when said cover is detached and being reversely movable into the interior of the casing.

11. In a lightwell, a casing comprising a main body portion having an open end, a portion for the egress of light, and a detachable closure for 10 said open end, a displaceable lamp holder having a body portion normally in said casing and being 15 provided with a lamp socket, said holder having internal space leading to said socket and in communication with the interior of said casing, electrical connections passing from the exterior to the interior of said casing including flexible conductors extending through the internal space of said holder and being electrically connected to said socket, an incandescent lamp in said socket, and guiding means whereby said holder is 20 slideable out of and into said body portion and is capable of being turned into an accessible position 25 outside of said body portion when said closure is 30 detached.

12. In a lightwell, a normally closed casing adapted to be opened and provided with a window, 35 a lamp holder normally fixedly positioned in said casing and retentively mounted for a combined sliding and turning withdrawal from and insertion into said casing when the latter is open, said lamp holder having a wall forming an interior 40 recess, there being an aperture through said wall into said recess, a lamp socket permanently held in said recess, a removable incandescent lamp in said socket near said window, and flexible electrical conductors extending through said aperture and recess to said socket and being electrically connected to said socket.

13. In a lightwell, a casing shell having open opposite ends, a cover removably attached to one end thereof, a light-permeable closure attached 50 and sealed to the opposite end of said casing, metallic terminals each having a base portion attached to said closure and oppositely projecting extensions therefrom formed for the attachment thereto of electrical conductors, an extension of 55 each terminal passing through said closure to the exterior thereof and another extension of each terminal being within said casing, an electrical lighting device normally in said casing having an illuminable portion in proximity to said closure, 60 said lighting device being mounted for withdrawal from said casing upon detachment of said cover, and flexible electrical conductors between said interior terminal extensions and said lighting device.

14. In a lightwell, a casing comprising a main body portion having an open end and an opposite end provided with a window, and a detachable cover for said open end, a lamp holder normally in said casing, an incandescent lamp inserted into 70 said holder near said window, a slotted guide, a member having a pin co-acting with said guide, said guide and member being one rigid with the interior of said casing and the other fast to said holder, said holder being movable when said cover 75

is detached out of and into said casing concomitantly with sequential relative sliding and pivotal movements of said guide and pin in the order dependent upon the direction of the movement of said holder, and electrical connections to said lamp holder.

15. In a lightwell, a casing comprising a main body portion having a window and an open end and a detachable cover attached to said open end, a slotted guide fast to and extending longitudinally of the interior of said body portion toward said open end, a lamp holder normally in said casing, an incandescent lamp inserted therein near said window, an element rigid with said holder and projecting into said guide, said holder being withdrawable until said element encounters the outer slotted end of said guide and thereafter being adapted to be pivotally turned into an accessible position, and being adapted to be reversely movable into said casing, and electrical connections to said lamp holder.

16. In a lightwell, a casing comprising a main body portion having an open threaded end and a window, and a threaded cover screwed onto said open threaded end, a slotted guide fixed to an intermediate portion of the interior of said body portion and extending toward its open end, a lamp-carrying holder having a body portion normally in said casing and an outer part upon which said cover is retentively and revolvably mounted, an element rigid with said holder and projecting into said guide, said cover and holder being adapted to be retracted until said element encounters the outer slotted end of said guide and to be thereafter pivotally turned into an accessible position exteriorly of said casing and being reversely returnable to their former positions, and electrical connections to said lamp holder.

17. In a lightwell, a casing comprising a main

body portion having an open threaded end, a sealed window and a threaded cover for said open end, a fixed guide interiorly of said body portion extending from an intermediate part thereof toward said open end, a lamp holder comprising a lamp-carrying portion normally in said body portion, a disk portion covering the open end of said body portion and a supporting portion retentively and revolvably mounting said cover, a seal between the open end of said body portion and the disk portion of said holder carried by one of them, an element rigid with said holder engaging said guide, said cover being adapted to be screwed off the open end of said body portion with an accompanying displacement of said holder and element, said element being slidable into a pivotal relation with the outer end of said guide whereby said cover and lamp holder may be turned into an accessible position exterior to said body portion while remaining connected thereto, reverse actuation of said cover and holder returning them to their former positions and sealing the open end of said body portion, and electrical connections extending from the exterior to the interior of said casing and to said lamp holder.

18. In a lightwell, a casing comprising a body portion having an open end and a removable cover therefor, a lamp-carrying holder movable out of and into said body portion, a fixed guide with which said holder is slidably connected, said guide extending longitudinally of said body portion toward said open end, displaceable flexible electrical conductors connected to said holder and extending longitudinally of said guide, and guides for said displaceable conductors in fixed relation to and projecting laterally from the first named guide.

ELLIOTT P. ROSS.
JAMES V. LAWRENCE.
